UNITED STATES PATENT OFFICE.

HARRY M. ZILE, OF WASHINGTON, DISTRICT OF COLUMBIA.

DESIGN FOR A WEIGHING-MACHINE.

48,431.

Specification for Design.

Patented Jan. 4, 1916.

Application filed October 5, 1915. Serial No. 54,289. Term of patent 14 years.

To all whom it may concern:

Be it known that I, HARRY M. ZILE, a citizen of the United States, and a resident of Washington, District of Columbia, have invented a new, original, and ornamental Design for Weighing-Machines, for which the following is a specification.

Referring more particularly to the accompanying drawing; the figure is a perspective view of the weighing machine, showing my new design.

In the illustrated embodiment characterizing my new and ornamental weighing machine, there is shown an upright member having a quadri-laterally shaped weight-supporting foot. The upper end of said upright has an annular enlargement provided with the usual dial and casing therefor. An ornamentation, in the form of a plate having its lateral edges artistically carved, producing in effect a mold-like scroll, is integrally formed with said annular enlargement, and

entirely surrounds the dial thereon. A rectangular casing, corresponding in width approximately to the diameter of the dial is integrally formed with the aforesaid upright and extends substantially throughout the length thereof. This casing supports a transparent medium, is formed with a plurality of vertically spaced compartments and has a laterally situated closure extending the length thereof. An additional casing centrally positioned immediately above the dial, combines with the other details hereinbefore described to produce an effect extremely ornamental and artistic.

I claim—

The ornamental design for a weighing machine, as shown and described.

HARRY M. ZILE.
